UNITED STATES PATENT OFFICE.

WINFIELD E. HINSDALE AND WILLIAM H. HALL, OF TRENTON, NEW JERSEY.

WATER-CLOSET.

1,391,477.

Specification of Letters Patent. Patented Sept. 20, 1921.

Application filed June 4, 1920. Serial No. 386,506.

To all whom it may concern:

Be it known that we, WINFIELD E. HINSDALE and WILLIAM H. HALL, citizens of the United States, residing at Trenton, in the county of Mercer and State of New Jersey, have invented certain new and useful Improvements in Water-Closets, of which the following is a specification.

This invention relates to an improvement in water closets wherein the shape of the rim and the water feed to same, whether in the regular shape bowl, or the vented bowl, is modified to procure a greater non-soiling condition and position of the rim and a more quiet feed of the flushing water to the rim than is possible in any of the existing models now made and procurable.

Two embodiments of the invention are disclosed in the accompanying drawings wherein,

Figure 1 is a vertical longitudinal section of a closet embodying our invention;

Fig. 2 a horizontal sectional view, the plane of the section being indicated by the line II—II of Fig. 1;

Fig. 3 a transverse vertical section taken on the line III—III of Fig. 1;

Fig. 4 a top plan view of the rear portion of the closet structure;

Fig. 5 a longitudinal sectional view of the rear portion of the closet showing the invention as applied to a closet having a local vent;

Fig. 6 a transverse vertical sectional view taken on the line VI—VI of Fig. 5; and

Fig. 7 a horizontal sectional view taken on the line VII—VII of Fig. 6.

Similar parts throughout the various views are indicated by the same reference numerals.

It will be understood that by reason of many years of use, the standardization of applied trimmings, and the necessity of a dimension standard, that the size of closets have become practically fixed, in that, it is only necessary for the general dealer to know that a measurement of $16\frac{1}{2}$ inches from the center of the seat post holes will reach the front of the closet, to enable him to procure seats to fit the same, or that an extended lip closet will go two inches farther forward and that the seat post holes are always $5\frac{1}{2}$ inches center. Also that the width of the bowl is fixed at 14 inches, and that the standard inside oval of the bowl

rim is 10×12 inches. This leaves the dealer

free to select his stock of seats independent of the style of closet used. Therefore, it is also evident that to secure a rim that will give greater non-soil efficiency, it is necessary to either enlarge the oval forward as 60 well as move the seat forward, thus destroying standards and creating greater expense in manufacture and carrying charge to the dealer and also a multiplication of his stock, or, move the rim back without disturbing 65 outside and fixed dimensions. When, however, the rim is moved back, we find that interference occurs with the rear of the bowl, with the water feed to the rim and with the seat attachment if the bowl contour is not 70 modified to overcome the interference. We have, notwithstanding this interference, moved the rear half of the inside oval of the rim to the rear and created a measure of 13 75 inches in the long diameter of the oval without moving the point of seat attachment or the outside oval of the bowl and rim.

The formation, contour and positioning of the oval with relation to the other parts is clearly indicated in the drawings, more 80 particularly Figs. 1 and 2, from which it will be noted that while the outside dimension of the bowl and rim is maintained standard, the inner dimension of the rim as regards its length or longitudinal axis, is 85 increased, and that the rim is narrowed at its rear portion. This arrangement does not in any wise affect the measurement for the seat attachment and the holes through which the seat attaching means are passed still 90 maintain their same relative distance from the forward portion of the bowl and rim.

It is evident that, by this disposition of the inside and outside ovals, the water way of the rim is nearly closed at the rear at the 95 point where common practice places the water control, which control is usually effected by a hole, of determined size, directly into the rim channel from the feed water chamber below the inlet and lying back of 100 the bowl and rim and below the closet top and the crown of the trapway with ducts leading downward to the actuating jet chamber.

We retain the feed water chamber of 105 practice, but having found that the water entering such chamber came immediately in contact with interposed air, which air had no outlet other than through the control orifice into the rim, such water became 110

mixed with the air and forced the air in its water mingled condition through the rim controlled orifices in an annoying noisy manner. This was particularly so in view 5 of the fact that the control orifice led directly into the rim at which point the commingled air and water was forced to pass to the right and left to travel around the rim requiring a noticeable period of time 10 for the air to become dispelled and a solid stream of water to be created. We have remodeled the structure so as to control the water entering the rim and take advantage of the entire section of the rear of the rim 15 coincident with the feed water chamber placed at that point, the rear wall of which chamber is formed by a bridge or diaphragm through which the control opening passes.

Referring first to Figs. 1 to 4 inclusive, 20 20 denotes the closet pedestal surmounted by the bowl 2. There is formed in the pedestal the usual siphon and trap passages 3 and 4, the latter leading to the outlet 5, all of which are of usual standard formation. The 25 closet rim is denoted by 6 and while the outer dimensions thereof remain standard the inner contour is changed so that the rear portion or passage of the rim is narrowed, as at 7. This is effected by elongating the 30 major axis of the inner oval of the rim. The rim is provided with the usual jet or stream orifices 8, some of which throughout the narrowed portion of the rim are made smaller, as indicated at 9, so as to cause the 35 water to flow around toward the wider forward portion of the rim and thus insure an even feeding of the water outwardly from the orifices throughout the rim.

The closet is provided with the usual 40 water inlet 10 which opens into a chamber 11 above the crown 12 of the trap, and supply passages 13 and 14, which extend downwardly along the sides of the siphon, the same terminating in the usual water supply chamber 15 into which opens the jet orifice 16. The diaphragm or bridge-like member 17 is placed across the forward end of the chamber 11, said member or bridge being spaced rearward from the rim proper 45 forming a secondary chamber 18 which at its forward portion opens directly into the rim, and a regulating opening 19 of determined size is formed in the bridge or diaphragm 17 and consequently controls and 50 determines the amount of water which may pass into the auxiliary chamber 18 and thence into the hollow rim. The openings for attachment of the seat securing means are indicated by 20 and as before stated said 55 openings bear the same relation to the outside dimensions of the bowl as in the usual standard closet so that the length of the inner oval and the inner dimensions of the rim do not in any wise affect the utilization 60 of seats of standard size.

Opening up the rear section of the rim by the provision of the auxiliary chamber 18 may be said to add that section of the rim to the chamber, thus allowing ample area in the rim channel on either side of 70 the forward end of the chamber 18 for the passage of water into the rim channel. It has the added advantage that as the water from the inlet 10 enters the water feed chamber 11 it falls first to the normal water 75 level of the bowl and chamber and as it rises forcing the air ahead of it to and through the control orifice or opening 19, where, entering the chamber 18 it finds largely increased area and its force is therefore destroyed before it gathers again to 80 enter the rim channel. The openings in the rim channel at the point of juncture or emergence of said channel with the chamber 18 are each approximately equal in area to 85 that of the control orifice or opening 19, the result being that the water flows easily into the rim channel and any air that may be commingled with the water at that time finds easy and quiet egress through the rim 90 apertures. By this method of construction we have obtained a quiet flushing closet and with a rim of continuous conventional oval form have obtained the maximum removal 95 of unwetted surface of the bowl and rim beyond the oval of the applied seat opening, eliminating thereby the heretofore distortions of the rims used by others in attempts to secure a similar result, and in so doing have confined our improved closet to the 100 accepted space details now more or less standard with all makers.

A second embodiment of the invention is shown in Figs. 5, 6 and 7, said closet being of the vented type. The closet embodies 105 the same idea of non-soil rim construction and there is present a vent passage or duct 21 originating in the bowl under the rear segment of the rim, thence passing upwardly above the trapway and under the extended 110 closet top, rising through the same at a point to the rear of the regular seat attachment and terminating at its rear entirely above the closet. No claim is made herein to such vent passage or duct, as that is set 115 forth and claimed in an application filed by Winfield E. Hinsdale, on or about the 17th day of July, 1917, Serial No. 181,069.

By reason of this vent passage or duct a slight modification in the water supply to 120 the rim is necessary. The water supply in this instance is designated by 22 and ducts or channels 23 and 24 pass downwardly to each side of the vent duct 21 to the jet actuating chamber 25. A chamber 26 corresponding to the chamber 18 of the form first described, is formed in the body of the closet in rear of the restricted portion of the flushing rim, and is in direct communication therewith. The rear wall of said 125 130

chamber is formed by the upper wall of the vent duct 21, and bridge pieces or dia- 5 phragms 27 and 28 are interposed between said wall and the rear portion of the chamber 10 26, control openings 29 being formed in each of said diaphragms and affording communication between said chamber 26 and the passages or ducts 23 and 24. These two 15 openings or orifices 29 are of determined size and perform the same office and function as the orifice 19 in the construction first described, but being made of a lesser area each, to equal in their sum the area of the orifice 19. In this closet, as in the 20 non-vented type, it will be seen that the falling water in a practically solid stream from the inlet reaches the normal water level before it can mix with any of the interposed air. Its weight immediately starts 25 the jet in action and the escape of water through the jet is not great enough to take the volume delivered and the excess of supply raises the water level to the rim controlled orific or orifices, which by reason of 30 its placement, as above set forth, allows easy escape for air and a consequent quiet entry of water into the flushing rim, the volume of which flow, as explained, being controlled by the predetermined size of the orifice 19 or the two orifices 29 in the construction last described.

It will be readily appreciated by those skilled in the art that the novel construction as to rim shape and rim water feed may be applied to closets of types other than the two herein specifically set forth, as the construction is readily adaptable to wash-down and ejector type bowls as well.

What is claimed is:

40 1. In a water closet, the combination of a bowl having a flushing rim, the channel wherein is of small cross area at the rear portion thereof as compared to the forward portion, said rear portion opening into a 45 chamber formed in the closet body, the front wall of which is coincident with the front wall of a portion of the rim at the rear of the bowl and the rear wall of which chamber has a control opening formed therein which is in 50 communication with the water supply of the closet.

2. In a water closet, the combination of a bowl having a flushing rim, the channel wherein is of a diminishing cross area toward the rear portion thereof, said rear portion opening into a chamber formed in the closet body, the front wall of which is coincident with the front wall of a portion of the rim at the rear of the bowl and the rear 55 wall of which chamber has a control opening formed therein which is in communication with the water supply of the closet.

3. In a water closet, the combination of a bowl having a flushing rim, the outer face 60 whereof is oval in plan while the inner face

is likewise of general oval outline, the walls of such faces lying closer to each other at the rear of the closet than at the front whereby the cross area of the rim is relatively small at the rear; and said reduced area rim opening into a control chamber formed in the closet body, the front wall of which is coincident with the front wall of said diminished rim. 70

4. In a water closet the combination of a bowl having a flushing rim, the cross sectional area whereof is smaller at the rear than at the forward portion thereof, a chamber located in the rear portion of the closet into which the flushing water enters and 80 from which it passes to the usual siphon jet nozzle; and a second chamber integral with and forming a part of the rear narrow portion of the flushing rim, said second chamber being in communication with the upper 85 portion of said first named chamber through an opening formed in a partition interposed between said chambers.

5. In a water closet the combination of a bowl having a flushing rim, the cross sectional area whereof is smaller at the rear than at the forward portion thereof, said rear portion being in communication with a chamber formed in the body of the closet forward of the usual supply chamber, said 90 supply chamber being integral with and forming a portion of the diminished section of the flushing rim; and means for controlling the supply of water to said chamber and the rim. 100

6. In a water closet the combination of a bowl having a flushing rim of constricted cross area at its rear; a siphon trap; and a jet nozzle in communication with a water supply chamber, the inlet whereof is at the 105 upper portion of the closet, said supply chamber being in communication with a rim supply chamber through an opening of determined area, said rim supply chamber being integral with and a part of the diminished section of the flushing rim. 110

7. In a water closet, the combination of a bowl having a flushing rim, the rear portion whereof is restricted in cross area and terminates as a part of and in a chamber formed 115 in the closet body, said chamber being in communication through an opening of determined size with the usual water supply of the closet, the cross area of said opening being approximately one-half that of the combined cross areas of those portions of the rim where they open into the chamber aforesaid. 120

8. In a water closet, the combination of a bowl having a flushing rim of the usual oval form and dimension as to its exterior face 125 with its inner face extended, without change of form so that it has an eccentric relation to said outer face.

9. In a water closet, the combination of a bowl having a flushing rim of the usual oval 130

- form and dimension as to its exterior face with its inner face extended rearwardly, without change of form, so that it has an eccentric relation to said outer face where-
5 by the cross area of said flushing rim is re-duced at its rear portion; and means for feeding water to said reduced rear portion.
10. In a water closet, the combination of a bowl having a flushing rim of the usual oval form and dimension as to its exterior face with its inner face extended rearwardly, without change of form, so that it has an eccentric relation to said outer face, whereby the cross area of said flushing rim is reduced 15 at its rear portion; a water supply chamber integral with and a part of said reduced portion, said chamber being in communication with the water supply passage of the closet through an opening of determined area.
- 20 11. In a water closet, the combination of a bowl, having a flushing rim of the usual oval form and dimension as to its exterior face with its inner face extended rearwardly, without change of form, so that it has an eccentric relation to said outer face, whereby the cross area of said flushing rim is reduced 25 at its rear portion; a water supply chamber integral with and a part of said reduced portion, said chamber being in communication with the water supply passage of the closet through an opening approximately one half the combined areas of those portions of the rim which open into the chamber aforesaid.
- 30 12. In a water closet, the combination of a bowl; a rim the inner face whereof is ex-35 tended rearward to produce a restricted channel in the rim at the rear of the bowl, said restricted portion opening into the side walls of a water supply and control chamber formed integrally with and a part of the restricted portion of the rim; a vent duct opening into the bowl below the rim, under-
lying the chamber aforesaid, and then ex-40 tending rearwardly and upwardly; a water supply discharging into a chamber which 45 overlies the vent duct and having ducts which pass downwardly to the usual jet nozzle of the closet; and means for controlling the flow of water from said last named chamber, as it rises therein, to the control cham-50 ber aforesaid.
13. In a water closet, the combination of a bowl; a flushing rim therefor, said rim at its rear opening into a water supply and control chamber therefor formed in the closet body integral with and a part of the rim and extending rearwardly to a rear wall formed by a bridge wall having an opening 55 therein of a size approximately one-half of the combined cross area of the ends of the 60 rim which open into said supply and control chamber.
14. In a water closet, the combination of a bowl having a flushing rim, the outer and inner faces whereof are oval in outline with 65 the inner oval so formed or elongated that the rim is narrower at its rear than through-out its other portions, the closet having the usual openings in the body thereof for seat attachment; a perforate bridge piece forming 70 the rear wall of a control chamber formed in the body of the closet, the front wall of the diminished portion of the flushing rim forming the front wall of said control chamber, the diminished section of the flushing 75 rim opening outwardly to the right and left from said control chamber at its forward end, and means for producing an upflow of water to said perforate bridge piece.
- In testimony whereof we have signed our 80 names to this specification.

WINFIELD E. HINSDALE.
WILLIAM H. HALL.
